UNITED STATES PATENT OFFICE.

LOUIS B. DENISON, OF DELAWARE, OHIO.

TRIPOD-HEAD FOR LEVELING-INSTRUMENTS.

SPECIFICATION forming part of Letters Patent No. 224,155, dated February 3, 1880.

Application filed August 12, 1879.

To all whom it may concern:

Be it known that I, LOUIS B. DENISON, of Delaware, in the county of Delaware and State of Ohio, have invented a new and Improved 5 Tripod-Head for Leveling-Instruments, of which the following is a specification.

Figure 1 is a plan of the device. Fig. 2 is a vertical section of the same on line *x x*, Fig. 1. Fig. 3 is a vertical section of the same on 10 line *y y*, Fig. 2.

Similar letters of reference indicate corresponding parts.

The object of this invention is to provide a device for the better adjustment or leveling of 15 surveyors' and engineers' field-instruments.

The invention may be described as follows: From near the periphery of a horizontal plate attached to and supported by legs, after the manner of tripods for leveling-instruments, 20 three equidistant rigid rods converge downward and pass through a smaller plate that is secured to them by nuts screwed on their ends or in some other safe way. Centrally secured upon the upper face of this plate is a short upward-projecting standard, on two opposite sides of which are pivoted two flat bars that project upward through a central opening in the upper horizontal plate and support there 25 an oblong metal box or frame that is without top or bottom. Two bars or plates are secured immovably and horizontally opposite each other across the edges of these flat bars, and pivoted between them is a square bar that projects upward centrally through the oblong box 30 and has a screw-thread cut on its end above the box. Two opposing screws supported by posts on the upper horizontal plate are applied to the opposite long sides of the box, while two like screws pass through the ends of the 35 box, and are applied to the square bar, that projects through it, and that is intended as a support for the leveling-instruments.

In the drawings, A represents the upper horizontal plate, provided with rectangular 40 opening *a'*, up through which the two flat bars B B project, carrying between them the oblong box C. The ends of these bars may be fashioned to make the sides or ends of the box, or the latter may be separately constructed and 45 secured to them.

D D are the converging rods connecting the

lower plate, E, with the upper plate, A. F is the standard, whose screw *f'* passes down through the plate E, and is secured to it by the nut *b'*. The flat bars B B, it is seen, are 55 pivoted on pin *c'*, that passes through them and the standard.

G is the square bar, that is pivoted on a pin, *d'*, that passes through it and the plates H H in a direction at right angles to the pin *c'*. 60 This square bar passes centrally up through the oblong box, and has a screw-thread cut in its upper end, on which will be secured the leveling-instruments and their attachments.

It will be seen that the flat bars supporting 65 the box C are adjustable in one plane, because of their being pivoted on a pin, *c'*, while the square bar is adjustable at right angles to the flat bars, because it is pivoted on the pin *d'*, and also in the same plane with the flat bars, 70 by reason of its being connected with them by the plates H H.

I I are the posts fixed on the upper face of the horizontal plate, and through them pass the screws K K, that adjust the level of the 75 box and square bar in one direction, while the screws L L, that pass through the ends of the box, adjust the square bar in the opposite plane. M M are the supporting-legs of the device, pivoted to the rectangular lugs N, that support 80 the upper horizontal plate.

It will be observed that in this device are two sets of leveling-screws, and the motions produced by them are independent of each other, so that when the instrument is leveled 85 over one set it remains so while being leveled over the other set. By this independence of motions the binding of the leveling-screws, that is so common with ordinary tripod-heads, is entirely obviated; and as the binding of the 90 screws is a source of a great deal of trouble to the operator in many ways, both because of the consequent breaking of the screws and because of the straining of parts of the tripod-head, the entire removal of such troubles by 95 the use of this device will recommend it to all who use leveling-instruments.

The device possesses other advantages that will readily be recognized by surveyors and engineers, and besides is exceedingly simple 100 and easily operated.

Having thus described my invention, I claim

as new and desire to secure by Letters Patent—

1. For leveling-instruments, the flat bars B B, oblong box C, rods D D, lower plate, E, standard F, square bar G, plates H H, pins c' and d', posts I I, and screws K K and L L, constructed and arranged substantially as herein shown and described.

2. The combination of standard F, bars B B, box C, bar G, plates H H, and pins c' and d', substantially as herein shown and described.

3. The combination of plate A, provided with opening a', with rods D D, plate E, and standard F, substantially as and for the purpose described.

4. The plate A, provided with the rectangular opening a', in combination with the posts I I and screws K K, substantially as and for the purpose described.

5. The legs M M and lugs N N, in combination with the plate A, having a rectangular opening, a', the box C, and the bars B B and G, substantially as herein shown, and for the purpose described.

6. In the construction of a leveling-instrument, the flat bars B B, pivoted to the standard F by the pin c', and supporting the box C, substantially as herein shown and described.

7. In the construction of a leveling-instrument, the square bar G, pivoted between the bars B B on pin d', that passes through the plates H H, which are fixed to the edges of the said bars B B, substantially as herein shown and described.

8. In the construction of a leveling-instrument, the plate A, provided with rectangular opening a' for the upward projection of bars B B and G, and for the purpose of permitting the adjustment of said bars and of the box C, substantially as herein shown and described.

9. In the construction of a leveling-instrument, the combination of rods D D and plate E, for supporting the standard F, substantially as herein shown and described.

10. In the construction of a leveling-instrument, the standard F, fixed in the plate E and supporting the bars G and B B, plates H H, and box C, substantially as herein shown and described.

LOUIS BASCOM DENISON.
